Primary Examiner — Katherine Glennon(74) *Attorney, Agent, or Firm* — Myers Wolin, LLC(57) **CLAIM**

The ornamental design for a productivity timer as shown and described.

DESCRIPTION

FIG. 1 is a perspective view of a first embodiment of a productivity timer showing our new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top view thereof;
 FIG. 7 is a bottom view thereof;
 FIG. 8 is a perspective view of a second embodiment of a productivity timer showing our new design;
 FIG. 9 is a front elevation view thereof;
 FIG. 10 is a rear elevation view thereof;
 FIG. 11 is a left side elevation view thereof;
 FIG. 12 is a right side elevation view thereof;
 FIG. 13 is a top view thereof; and,
 FIG. 14 is a bottom view thereof.
